HARNESS MECHANISM FOR LOOMS

Oscar V. Payne, Leicester, Mass., assignor to
Crompton & Knowles Loom Works, Worcester,
Mass., a corporation of Massachusetts

Application May 27, 1944, Serial No. 537,603

8 Claims. (Cl. 139—55)

This invention relates to improvements in harness mechanisms for looms and it is the general object of the invention to provide means by which the bearings for the harness connector sheaves may be wide enough to resist objectionable wear.

Warp threads of looms are controlled by harness frames which are generally raised through flexible connectors extending around harness sheaves and connected to some form of harness lifting mechanism, such as a dobby or Knowles head. It has been customary in the past to place all of the harness sheaves on a single supporting shaft with the result that the sheave bearings have been too narrow to withstand the wear incident to the repeated rockings in opposite directions occurring during loom operation. It is an important object of my present invention to provide means for supporting the sheaves in two sets or groups in such a way that the sheaves of one group are staggered with respect to the sheaves of the other group, thereby permitting the use of wider sheave bearings.

In the correct alignment of the warp sheds it is necessary to be able to raise and lower the harness frames with respect to the loom. It is another object of my present invention to provide carrier means for the sheave shafts so constructed that the latter may be adjusted vertically with respect to the loom arches so that both groups of sheaves may be given their correct positions.

It is a further object of my invention to provide an improved sheave shaft support so constructed that it can be readily attached to the loom arches and afford means for independent adjustment of the two groups of harness sheaves. The support is made so that it can be slid along the loom arches for adjustment with respect to the harness lifter mechanism and the harness frame.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of the upper part of a loom showing harness frames and harness lifting mechanism together with my improved mounting for the harness sheaves.

Fig. 2 is a detail plan view of one pair of sets of sheaves looking in the direction of arrow 2, Fig. 1, with the harness frames omitted.

Fig. 3 is an enlarged vertical section on line 55

3—3 of Fig. 2 showing one of the aforesaid supports and the manner in which it is mounted on the loom arch corresponding thereto,

Fig. 4 is a vertical section on line 4—4 of Fig. 3.

Fig. 5 is a horizontal section on line 5—5 of Fig. 3.

Fig. 6 is a perspective view of one of the sheave stands or supporting blocks, and

10 Fig. 7 is a detail showing one of the carriers for the sheave shaft supporting screw, partly in section, with part of the screw detached therefrom.

Referring particularly to Figs. 1 and 2, I have shown a loom frame 10 across the upper part of which extends front and back arches 11 and 12, respectively. These arches may be of the usual form having a vertical web 13 and upper and lower flanges 14 and 15, respectively. The flanges of the front arch extend rearwardly from their corresponding web 13, while the flanges of the rear arch 12 extend forwardly. Supported on the loom arches is any convenient form of harness lifting mechanism indicated generally at K and including a series of harness jacks two of which are shown at 16 and 17 in Fig. 1. These jacks operate in usual manner and are shifted during loom operation so that each jack may occupy both of the positions indicated in Fig. 1.

20 The loom is provided with a set or plurality of harness frames for the warp threads, two of these frames being indicated at 20 and 21 in Fig. 1. The vertical position of these frames is determined by the mechanism K acting through harness connections indicated generally at the upper part of Fig. 1. Thus, as indicated in Fig. 1 the front harness frame 20 is connected by harness cords 22 and 23 to a link 24 received by one or another of the notches of harness jack 16, while the rear harness frame 21 is similarly connected by cords 26 and 27 to a second link 28 connected to the harness jack 17. These several cords are connected to their respective harness frames by hooks 29 extending upwardly from the top rails of the harness frames.

30 In the past it has been common practice to train the harness cords from one end of the loom around one set of sheaves all rotatable on a single shaft and train the harness cords leading from the other end of the loom around a similar set of sheaves also mounted on a single shaft. By this construction it is necessary to reduce the width of the sheave bearings to an amount equal substantially to the thickness of the harness

frames. It has been found that when harness sheaves are made in this way they are subject to rapid wear especially when it is realized that lubrication of the sheaves is rendered difficult because of the fact that they are located directly over the warp threads.

The matter thus far described is of common construction and is set forth for illustrative purposes to indicate one manner of using my invention. The jacks 16 and 17 can be parts either of the well-known Knowles head or dobby, and the customary means not shown herein may be employed for pulling the harness frames downwardly when a harness frame shifts from a position corresponding to jack 17 to a lower position.

In carrying my present invention into effect I provide two sets or groups of harness cord sheaves for each end of the loom and stagger the sheaves of one group with respect to the sheaves of the other group so that the harness cords may be properly aligned and in order also that the sheaves may be provided with bearings substantially twice the width of those heretofore used. Since the pair of sets or groups at the two ends of the loom are similar I will give a detailed description of those located at the left end only as seen in Fig. 1, and it will be understood that this description suffices for the sheaves at the right end of the loom also.

As indicated in Fig. 2 the two sets or groups 35 and 36 of the harness sheaves nearest the harness lifter mechanism K extend between the front and back arches and are held in position on supports or blocks B, one behind the other, and secured adjustably along the length of the front and back arches. These supports are both alike and are shown in Fig. 6, each support comprising a wall 40 slotted as at 41 to receive a bolt 42 passing through the associated arch. Each wall has extending laterally from the ends thereof wings 43 and 44 each terminating in a vertical member 45 slotted as at 46. The slots 46 provide inner walls 47 and outer walls 48 extending vertically, and slot 46 is preferably though not necessarily machined in order to provide smooth guideways for structure to be described. The upper and lower ends of each of the walls 47 and 48 are formed with concave surfaces or pockets, as at 50, and any pair of concave surfaces at the same ends of guide walls 47 and 48 are preferably concentric about an axis parallel to the length of block B, and extending transversely of the associated guide slot 46. The support 40 is symmetrical as will be apparent from Fig. 6 so that it may be used on either the front or rear arch, and may if desired be inverted. There will be four of these supports 40 for each loom, two for each pair of sheave groups.

Each of the upper pairs of concave surfaces 50 receives a cylindrical carrier 55 extending across the upper end of the corresponding slot 46 and positioned substantially parallel to the adjacent arch by the concave surfaces 50. Each carrier is provided with a clear hole 56, see Fig. 7, extending vertically therethrough to receive the upper end of a screw threaded bolt 58. These threads extend through but are not tapped into the hole 56 so that the bolt may be moved vertically with respect to the carrier 55 while the latter is seated in the associated concave pockets 50. The lower end of each bolt is provided with a head 59 on which rests a sheave supporting means, such as a shaft 60, provided with a vertical bore 61 through which the lower unthreaded end of the bolt passes, see Fig. 3.

A winged nut 65 is threaded on the upper end of bolt 58 and as shown more particularly in Fig. 4 has the lower surface thereof provided with a concave groove 66 which fits over the upper part 5 of a carrier 55 for the purpose of holding the winged nut against turning with respect to the bolt when said nut has been properly adjusted.

It will be understood from an inspection of Fig. 2 that the sets or groups 35 and 36 of sheaves extend between two of the supports 40 and are mounted on two parallel shafts 60 each supported as shown more particularly in Fig. 4 and held in vertically adjusted position by the bolt head 59 and the winged nut 65. These shafts 60 are parallel and extend horizontally between the front and back arches and have mounted thereon harness cord sheaves S one of which is shown particularly in Fig. 4. Each sheave has a peripheral groove 70 to receive the associated harness cord and has a web 71 formed integral with a hub 72. An anti-friction or oilless bushing 73 may be driven into each hub 72 if desired. The bearing hubs 72 are approximately double the widths of the usual sheave and therefore provide much improved bearing surfaces requiring less frequent replacements and affording better operation. The web, or plane of the rim 70, may be central with respect to the ends of the associated hub 72, as seen clearly in Fig. 4.

Each set of sheaves is arranged on its associated shaft 60 so that the sheaves thereof will be staggered laterally with respect to the sheaves of the other set, as indicated in Fig. 2. In order to effect this staggering I use collars 75 which are approximately half the width of a bearing hub 72. As shown in Fig. 2 the sheaves are strung along the left hand shaft 60 so that the front sheave is close to the front arch 11, while the rearmost sheave is spaced from the rear support 40 by a collar 75. The right hand group 35 of sheaves on the other hand is arranged on its shaft 60 in reverse order, having the collar 75 at the front of the group. Since each collar extends along its shaft a distance equal substantially to one-half the length of a sheave hub, these collars when arranged as shown in Fig. 2 effect staggering of the sheaves of one group with respect to the sheaves of the other group, the sheaves of one set lying intermediate or half way between the sheaves of the other set.

Although only two harness jacks have been mentioned thus far, as a matter of fact the loom will be provided with as many harness jacks as there are harness sheaves in each pair of groups, and from this it is to be understood that there will be a number of jacks behind each of the jacks 16 and 17 as shown in Fig. 1. The harness cords associated with the front harness jack 16 and with alternate jacks reading from front to back, Fig. 2, will have their cords trained around group 36 of sheaves, while the cords corresponding to the intermediate jacks will be trained around the sheaves of the groups 35 and lead to the intermediate harness frames, starting with frame 21. Thus each harness jack is connected to its corresponding harness frame at two spaced points and extends around the sheave belonging to a group spaced from the group associated with the adjacent jack. In this way the harness cords are kept substantially parallel and in proper alignment.

As previously mentioned, the right hand groups of sheaves shown in Fig. 1 will be the same as those more particularly described in connection

With the left hand groups, and it will also be understood that if desired the groups 36 may be held at a lower level than groups 35 by proper manipulation of the associated winged nuts. While it is desirable to maintain a difference of level between the groups of any pair of groups as indicated in Fig. 1, yet I do not wish necessarily to be limited to this arrangement. It will also be understood that the staggering for the right hand pair of groups will be substantially the same as that shown in Fig. 1 for the left hand pair of groups.

From the foregoing it will be seen that I have provided a simple form of harness cord sheave mechanism wherein the rims and hubs of the sheaves of two adjacent sets 35 and 36 of sheaves are staggered laterally with respect to each other, or in the direction of the length of shafts 60, so that their hubs may be of substantial length and extend along the supporting shafts 60 for a distance approximately double that heretofore used. In each pair of sheave sets there is a sheave for each harness frame, but the cords trained over the sheaves of one set will lead to alternate harness frames, while the cords from the other set lead to the intermediate frames. This may conveniently be accomplished by having the sheaves over their corresponding harness frames. It will further be seen that I have provided an improved harness sheave supporting block, constructed substantially as shown in Fig. 6 and having spaced vertical guide slots for the shafts 60 and having also concave pockets 50 which receive the carriers 55 through which pass the shaft supporting bolts 58. The block is adjustable along the harness frame by reason of the slot 41 and bolt 42 and fits between the top and bottom rails 14 and 15 of the associated arch. The blocks for the loom are all alike and are symmetrical about a horizontal plane passing through a slot 41 so that the block may be inverted should the pockets 50 become worn. Furthermore, the block carrier 55 and bolt 58 provide an improved supporting and adjusting unit for the sheave shaft.

Having thus described my invention it will be seen that changes and modifications may be made therein by those skilled in the art without departing from the spirit and scope of the invention and I do not wish to be limited to the details herein disclosed, but what I claim is:

1. In harness mechanism for a loom having front and back arches, a pair of blocks, one secured to each arch, a pair of shafts extending between and supported by said blocks, and a set of harness sheaves on each shaft, the sheaves of each set being equally spaced by a given distance and the sheaves of one set being staggered with respect to the sheaves of the other set laterally in the direction of the length of said shafts, a collar on one shaft between the block on the front arch and the corresponding set of sheaves and a second collar on the other shaft between the block on the back arch and the other set of sheaves, said collars having a width measured along said shafts equal to one-half of said given distance.

2. In harness sheave supporting mechanism for the arches of a loom having a plurality of harness frames, two parallel horizontal shafts extending between the arches, a set of sheaves on each shaft, the sheaves of one shaft being over alternate harness frames and the sheaves of the other shaft being over the intermediate harness frames, said sheaves all being similar and having hubs on their respective shafts, a collar on one of said

shafts spacing the sheaves on said one shaft toward one of the arches, and a collar on the other shaft spacing the sheaves on said other shaft toward the other arch.

3. In harness sheave supporting mechanism for the front and back arches of a loom having a plurality of harness frames, a set of sheaves on each shaft, each sheave having a hub and a rim the plane of which lies intermediate the ends of the hub thereof, a collar at the rear end of one of said shafts engaging the hub of the rearmost sheave on said one shaft, and a similar collar on the front end of the other shaft engaging the hub of the foremost sheave on said other shaft, the length of said collars measured along the shafts being substantially one-half the length of a hub and said collars causing the rims of the sheaves on one shaft to be staggered laterally with respect to the rims of the sheaves on the other shaft.

4. In a harness sheave supporting block for the arch of a loom provided with a set of sheaves on each of two horizontal shafts, said block having an elongated horizontally extending wall for attachment to said arch, a wing extending laterally from each end of the wall, vertically extending means on each wing defining a vertical guide slot for one of the shafts, one slot for each shaft, each of said means having bearing surfaces on the upper parts thereof on opposite sides of the corresponding slot, said bearing surfaces being concave about a common axis substantially parallel to the length of said wall.

5. In a harness sheave supporting block for the arch of a loom provided with a set of sheaves on each of two horizontal shafts, said block having an elongated horizontal wall having a central slot extending longitudinally thereof and centrally with respect to the top and bottom of the wall, a pair of spaced guides extending vertically on each end of the wall, each pair of walls defining a vertical guide slot for a shaft, and the tops and bottoms of each pair of guides having concave surfaces the axes of which are substantially parallel to the length of said wall, the concave surfaces on the tops and bottoms of said guides being symmetrically spaced about a horizontal plane passing centrally of said slot.

6. In a harness sheave supporting block for the arch of a loom provided with a set of sheaves on a horizontal shaft, said block having provision for attachment to the arch, and being formed with a vertical slot open at the top and bottom thereof to receive said shaft, and the block being formed with a pair of coaxial concave pockets adjacent to each end of the slot, the axis of said pairs of pockets being parallel and extending across said plate.

7. A supporting unit for the harness cord sheaves of a loom having an arch, said unit comprising a block secured to the arch, vertical guides on the block spaced to define a vertical guide slot, a horizontal shaft extending into said slot, a supporting bolt for the shaft extending upwardly through the slot, said guides having concave surfaces on each side of said slot, a cylindrical carrier resting on said concave surfaces and extending across the top of the slot and through which the bolt passes, and means on the upper end of the bolt resting on said carrier to support the shaft.

8. A supporting unit for the harness cord sheaves of a loom having an arch, a block having a wall extending along and secured to the arch,

a pair of vertically extending spaced walls projecting forwardly from the block, a horizontal shaft extending into the slot, support means passing through the end of the shaft and located in said slot, the upper surface of said walls having concave surfaces concentric about an axis which is transverse of said walls, a cylindrical carrier in said concave surfaces resting on both

5 of said walls and extending across the slot and through which said supporting means extends, and means on the upper end of the supporting means above said carrier and resting on the latter to support said supporting means and the shaft.

OSCAR V. PAYNE.
